United States Patent Office

Des. 202,301
Patented Sept. 14, 1965

202,301

CONTAINER FOR A FILM REEL

Lazzaro A. Fattori, 84 Rose Ave., Woodcliff Lake, N.J.

Filed Sept. 28, 1964, Ser. No. 81,897

Term of patent 14 years

(Cl. D58—12)

FIG. 1 is a top perspective view of a container for a film reel showing my new design;

FIG. 2 is a side elevation view, the other three sides being the same in appearance; and

FIG. 3 is a bottom plan view thereof.

I claim:

The ornamental design for a container for a film reel, as shown and described.
